(57) **CLAIM**

We claim the ornamental design for a collapsible five legged stepstool, as shown and described.

DESCRIPTION

FIG. 1 is a front perspective view of the collapsible five legged stepstool of our design;

FIG. 2 is a right-side elevation view thereof, the left-side elevation view being a mirror image thereof;

FIG. 3 is a front elevational view thereof;

FIG. 4 is a rear elevational view thereof;

FIG. 5 is a top plan view thereof; and,

FIG. 6 is a bottom plan view thereof.

Where included, broken lines showing environment or structure are for illustrative purposes only and form no part of the claimed design.
